KEY CASE PLATE

Albert A. Zarowin, Brooklyn, N. Y., assignor to
Eveready Keyholder Co., Inc., a corporation of
New York

Application March 23, 1946, Serial No. 656,608

5 Claims. (Cl. 70—456)

1

This invention relates to an improved key holder, and one of its objects is to provide a keeper plate with a main bead and an auxiliary bead and a rod slideable in the auxiliary bead to close all of the slots formed in both beads and constructed so that it will not accidentally shift endwise and become separated from the keeper plate, so as to cause any of the key hooks to work out of its cooperating slot.

The present invention embraces certain refinements and improvements over the construction shown in my previous Patent 2,232,503, issued Feb. 18, 1941, for Key case. In the construction shown in this patent the shank of the lever slides through a minor bead of the keeper plate, and is provided with a handle or crank arm on its outer end, which is manually inserted in the slot formed by an auxiliary lug and the adjacent end of the keeper plate. It frequently happens that this handle arm will be displaced from its holding slot, and when this occurs the shank of the lever will shift endwise, so as to accidentally release the key hooks. It is impossible to lock the lever except by forcing the handle into the additional slot formed at the end of the keeper plate, and this slot is not employed in any way to hold a key hook. It involves additional construction and frequently fails to prevent accidental unlocking of the lever.

In the present invention the rod is formed with a series of offsets which cooperate with the slides of the slots, through which the individual key holding hooks swing and swivel, so that the rod is held by the frictional engagement of these offsets from accidentally shifting endwise to release any or all of the key holding hooks, but may be manually shifted when desired to permit of the release of any or all of the key holding hooks.

With the above and other objects in view, the invention relates to certain new and useful constructions, combinations and arrangements of parts, clearly described in the following specification, and fully illustrated in the drawings, in which—

Fig. 1 is a plan view, enlarged of the keeper plate, showing one key holding hook in normal position, a fragment of the key case being shown.

Fig. 2 is a transverse sectional view, taken on line 2—2 of Fig. 1, looking in the direction of the arrows.

Fig. 3 is a fragmentary transverse sectional view, further enlarged, illustrating the maximum frictional position of the locking rod.

Fig. 4 is a similar view, illustrating the minimum frictional position of the locking rod.

Fig. 5 is a detail sectional view of the rod in the position shown in Fig. 3.

Fig. 6 is a detail sectional view of the rod in the position shown in Fig. 4.

2

Fig. 7 is a plan view of the locking rod by itself.

Fig. 8 is a vertical longitudinal sectional view, taken on line 8—8 of Fig. 1, looking in the direction of the arrows, with the locking rod entirely removed.

Referring to the drawings, which illustrate the practical embodiment of the invention, 5 designates a flexible case, which may be of leather or other suitable material, to which the metal keeper plate 6 is attached by the eyelets or fasteners 7.

This plate is formed with a main bead 8, which extends from one side edge of the plate to the other side of the plate, and which is parallel to the upper longitudinal edge of the plate. This upper longitudinal edge of the plate is formed with a minor tubular bead or edge roll 9, considerably smaller in diameter than the main bead 8. The plate is also formed with transverse slots 10, which extend through the main and minor beads, and thus through the upper edge of the plate.

Both sides of the plate 6 are formed alike, so that the key hooks may be mounted on the case 5 in proper balanced relation thereto.

The minor bead or edge roll 9 is formed by curling the upper and divided edge of the keeper plate under the main bead, thereby concealing the raw edge of the plate in the main bead.

In each of the slots 10 the shank 11 of a key holding hook 12 is arranged to swing and swivel, and each shank is formed with a head 13 which is wider than the slot and which normally prevents the shank from pulling out of the slot. The individual key holding hooks are prevented from moving through the upper ends of the slots by means of the rod 14, which is inserted in the divided bead or edge roll 9. In this case the shank of this rod is formed with offset portions or small loops 15, which are adapted to register with the slots 10. All of these offsets or loops are disposed in a common plane, and the rear end of the rod is formed with a loop 16, to aid in pushing the rod in place and in sliding it in position.

The bore of the edge roll or minor bead 9 is formed slightly elliptical in transverse cross-section so that it will have a vertical length 50 slightly in excess of its width, thereby producing an elliptical bore within the edge roll or bead.

When the rod 14 is in the position shown in Figs. 1, 2 and 3, the offsets will have maximum frictional engagement with the sides of the slots, 55 or the edges 17 of the lugs formed by the slots 10, and maximum manual effort will be required to affect the withdrawal of the locking rod. When the locking rod is in the position shown in Fig. 4 the offsets will be disposed above the locking rod 60 and due to the elliptical form of the opening of

the minor bead or roll the entire locking rod and its offset loops will be under minor frictional pressure from the curls of the minor bead or edge roll, so that in this position the locking rod may easily be withdrawn by manual effort.

By this construction the locking rod is retained in locking position against accidental endwise sliding, and cannot freely shift in either position it may assume, unless manual pulling effort is applied to the handle of the rod. This handle does not in any manner having any locking function, as it projects endwise of the keeper plate without entering any locking slot or engaging any stop or locking lug.

The offset loops present rounded surfaces which are adapted to have sliding engagement with the edges of the slots, so that the use of the rod has a natural tendency to polish these edges to make the swinging of the hooks smoother. When the offset loops are disposed in the position shown in Fig. 1 they have a tendency to increase the internal pressure on the curls of the edge roll or minor bead, and this naturally increases the resistance to sliding of the locking rod.

This construction not only improves the product value of the key case, but reduces cost of construction, and provides for greater security for the owner of the keys which are protected by the improved key case.

I claim as new and patentable:

1. A key holding plate for key cases, comprising a plate having a main bead disposed in parallel relation to one edge thereof and having a curled edge forming a minor tubular bead having a bore opening therein, said plate having a slot extending through said main and minor beads, a key holding hook having a shank which is freely slideable in the slot through both beads and which is provided with a head which is wider than the slot, and a rod slidably disposed in the bore opening of the minor bead and provided with an offset loop engageable with the sides of said slot, the minor bead and the bore opening thereof being elliptical in transverse cross section to permit the offset loop to pass through said bore when said loop is disposed inwardly of the outer edge of the minor bead and in alignment with said bore, whereby longitudinal sliding of the rod through said bore may be made.

2. A key holding plate for key cases, comprising a plate having a main bead disposed in parallel relation to one edge thereof and a curled edge forming a minor tubular bead approximately elliptical in transverse cross section and having a bore of corresponding shape, said plate having a series of slots extending through said main and minor beads, a key holding hook having a shank freely slideable in any one of said slots and having a head which is wider than any slot, and a locking rod slidable in the bore of the minor bead and having offset loops spaced apart from each other to simultaneously register with all slots, said loops being disposed in a common plane and being slideable in the elliptical bore of the minor bead and said rod being turnable in said bore of the minor bead to cause said loops to project toward the outer edge of said minor bead and lock said rod against longitudinal movement in said bore, and a handle on the outer end of 70 said rod.

3. A key holding plate for attachment to key cases, comprising a plate having a main bead

disposed in parallel relation to one edge thereof and a curled edge forming a minor tubular bead, said plate having a series of slots parallel to each other which extend through both said beads, a 5 key holding hook having a shank which is freely slideable in any of said slots and having a head wider than any of said slots, the curled edge of said minor tubular bead being elliptical in transverse cross section and the bore of said minor tubular bead being of corresponding shape, and a locking rod slideable in the bore of the minor bead and having a series of offset loops disposed in a common plane and spaced from each other to have matching engagement with the sides of 15 all of the slots of the minor bead, the offset loops being adapted to lock the rod in said minor bead when disposed outwardly thereof and to permit sliding of said rod in said minor bead when disposed inwardly thereof to register with said elliptical bore of the minor bead.

4. A key plate having a longitudinally arched upper-edge portion and a series of transverse slots extending through said arched portion and parallel to each other, the upper edge of the plate being formed with a tubular bead of approximately elliptical shape in transverse cross section and with a bore having corresponding shape and said slots extending through said bead, each of said slots being adapted to receive the shank 25 of a key holding hook having a terminal head wider than the slot, and a rod slideable in the bore of the bead and provided with a series of offset portions disposed in a common plane and spaced apart from each other a distance corresponding to the spacing between the slots so that said offset portions will simultaneously engage the side edges of said slots to latch the rod in said bead, the rod being released from said slots by turning the same in said bead so that the 30 offset portions will register with the major axis of the bore of said bead.

5. A key plate having a main bead on its upper longitudinal edge portion and a curled edge providing a tubular minor bead of approximately elliptical shape in transverse cross section and having a bore of similar shape, said plate having a transverse slot extending through said main and minor beads, a key hook having a shank which may freely slide in said slot and having a head wider than the slot to retain the shank in said slot, and a rod slideable through the bore of said minor bead across the slot of the minor bead to prevent accidental withdrawal of the shank from the slot of said minor bead, said rod having a laterally offset portion receivable by said slot to prevent accidental longitudinal movement of said rod, said rod being turnable in said minor bead to locate said offset portion in alignment with the minor bead bore to permit 55 said offset portion to pass through said bore and the rod out of said minor bead.
